US00D830374S

(12) **United States Design Patent** (10) **Patent No.:** **US D830,374 S**
Leonard et al. (45) **Date of Patent:** ** *Oct. 9, 2018

(54) **DISPLAY SCREEN OR PORTION THEREOF WITH A GRAPHICAL USER INTERFACE**

(71) Applicant: **Bred Ventures Inc.**, Glendora, CA (US)

(72) Inventors: **Edwin R. Leonard**, Glendora, CA (US); **Bryan Ezra Clay**, Glendora, CA (US)

(73) Assignee: **BRED VENTURES INC.**, Glendora, CA (US)

(*) Notice: This patent is subject to a terminal disclaimer.

(**) Term: **15 Years**

(21) Appl. No.: **29/580,397**

(22) Filed: **Oct. 7, 2016**

(51) **LOC (11) Cl. 14-04**

(52) **U.S. Cl.**

USPC **D14/485**

(57) **CLAIM**

We claim the ornamental design for a display screen or portion thereof with a graphical user interface, as shown and described.

DESCRIPTION

The sole FIGURE is a front view of a display screen or portion thereof with a graphical user interface.

The broken line showing of a display screen with graphical user interface is included for the purpose of showing portions of the article which form no part of the claim.

1 Claim, 1 Drawing Sheet
